US0D1051746S

(12) **United States Design Patent** (10) Patent No.: **US D1,051,746 S**
(45) Date of Patent: ** Nov. 19, 2024

(54) **TEST DEVICE FOR CAN BUSSES**

(71) Applicant: **GEMAC Chemnitz GmbH**, Chemnitz (DE)

(72) Inventors: **Marcel Ebert**, Arnsdorf (DE); **Bastian-Jirko Spinger**, Arnsdorf (DE)

(**) Term: **15 Years**

(21) Appl. No.: **35/520,088**

(22) Filed: **Feb. 2, 2024**

(80) **Hague Agreement Data**

Int. Filing Date: **Feb. 2, 2024**

Int. Reg. No.: **DM/235164**

Int. Reg. Date: **Feb. 2, 2024**

Int. Reg. Pub. Date: **Feb. 23, 2024**

(30) **Foreign Application Priority Data**
